COVER OPERATED THERMOSTAT

Ralph E. Drummond, Bell, and John W. Wright, Long Beach, Calif., assignors to Robertshaw-Fulton Controls Company, Richmond, Va., a corporation of Delaware

Application March 20, 1958, Serial No. 722,810

4 Claims. (Cl. 200—138)

This invention relates to control devices and more particularly to a bimetal actuated thermostat.

It is an object of this invention to control the ambient temperature by manual manipulation of the cover of a control device.

It is another object of this invention to provide a simple adjustment or calibration means for a control device.

It is another object of this invention to fixedly mount a temperature indicating device regardless of movement of a temperature control device.

It is a further object of this invention to provide means to insure disengagement of a pair of contacts when a cover member is rotated to the "off" position.

It is still a further object of this invention to make the parts of the control device easily accessible in the event service is required.

These and other objects will become apparent from the following detailed description taken in connection with the accompanying drawings wherein:

Fig. 1 is a front view of the control device embodying this invention;

Fig. 2 is a cross-sectional view of the device shown in Fig. 1; and

Fig. 3 is a sectional view taken along line III—III of Fig. 2.

Referring more particularly to the drawings, a control device, indicated generally at 10, includes a circular base member 12 which is adapted to be secured in a vertical position by screws (not shown) driven into a wall or suitable mounting surface through a pair of mounting apertures 14 provided in the base. The base 12 is provided with a centrally disposed boss 16 having a square opening 18 therethrough. A center post or shaft 20 is provided with a non-circular, preferably square-shaped reduced portion which is split to form legs 22. The legs 22 are slidably received in the opening 18 and due to their shape, rotation of shaft 20 is prevented.

Rotatably mounted on the upper portion of boss 16 is a generally elongated member which forms a first lever 24. Lever 24 is held in place by a U-shaped clip 26 which is secured to the base 12 by suitable fastening means 28. A flange 30 extends from one end of the lever 24 and has one end of a bimetal strip 32 attached thereto by rivets 34. The bimetal strip 32 has a substantially circular configuration with the high expansion element situated on the inner side thereof.

The other end of the bimetal is bent inwardly so as to form a portion of a radius of the circular configuration and has a contact 36 of a pair of contacts 36, 38 resiliently connected thereto. More particularly, a substantially U-shaped armature 40 has one leg fastened to a bimetal 32 and a leg of a substantially U-shaped spring clip 42 is attached to the other leg of the armature by a rivet 44. The U-shaped armature 40 and the U-shaped spring clip 42 are positioned in mating relation and the contact 36 is secured to the other leg of the spring clip 42 and extends through an aperture 46 formed in the bimetal 32 and the armature 40. The contact 36 is

2

adapted to be moved into and out of engagement with contact 38 by bimetal 32 in response to changes in ambient temperature.

The contact 38 comprises a screw which is threadedly received by the outwardly extending leg of an angular member 48 which is secured to the base 12 by rivets 50. A permanent magnet 52 is also attached to the outwardly extending leg of angular member 48 and is adapted to encircle the contact 38. It is apparent that the permanent magnet 52 attracts the armature 40 to close the contacts 36, 38 and that the screw contact 38 may be rotated to adjust the holding force thereof.

Means is provided to move contact 36 relative to contact 38 to vary the temperature at which the contacts 15 will open or close. This means includes a second lever 54 which is pivotally mounted on a pin 56. The pin 56 is attached to the base 12 and extends outwardly therefrom. The lever 54 is of a V-shaped configuration and has one of its legs adjustably connected to the first lever 20. This connection comprises a screw 58 which is threadedly mounted on a flange 60 of a lever 24 and a coil spring 62 which has one end fastened to the base 12 and the other end fastened to the lever 24. The spring 62 urges the lever 24 in a clockwise direction about shaft 25 to cause engagement of the screw 58 with the lever 54.

The other leg of lever 54 is adapted to ride on a cam surface 64 formed on the inner portion of a cover 66 which is adapted to protect the parts of the device. The cover 66 is of generally cup-shaped configuration and has 30 a centrally disposed annular flange portion 68 which is rotatably positioned on the shaft 20. Resilient means 69, composed of two separate springs, is disposed around shaft 20 between the clip 26 and flange 68 to bias the flange 68 against a shoulder 70 on the shaft 20. The cover 35 66 is also provided with a downwardly extending peripheral flange 72 which forms a shield for the parts while still permitting free flow of air thereto.

Mounted on the shaft 20 within the cup-shaped recess of cover 66 is a circular dial face 74 having an appropriate scale 76 thereon. A pointer 78 is fixedly mounted on the cover 66. The cover 66 is adapted to be manually rotated to move the pointer 78 relative to the scale 76 to select the temperature condition at which the contacts 36, 38 are to close to operate appropriate air conditioning or other controlled equipment (not shown).

When the cover 66 is rotated in a clockwise direction to move the pointer 78 to a higher setting on dial face 74, lever 54 rides down the cam surface 64 and thereby rotates in a counter-clockwise direction about pin 56. 50 A pair of stop pins 80 are mounted on the base 12 and are adapted to engage a pair of projections 82 formed on the inner portion of cover 66 to limit the range of rotation of the cover 66.

Upon counterclockwise rotation of lever 54, the coil spring 62 maintains the screw 58 in contact with lever 54 thereby causing clockwise rotation of lever 24 about shaft 20. This clockwise rotation of lever 24 moves bimetal 32 and contact 36 attached thereto toward and into engagement with the base mounted contact 38. It is now apparent that a higher ambient temperature will be required to actuate the bimetal 32 to move contact 36 out of engagement with contact 38. Thus, the conditioning equipment will operate to increase the ambient temperature until the higher temperature is reached and contact 36 disengages contact 38. Conversely, when the cover 66 is rotated in a counterclockwise direction, a lower ambient temperature will be required to open contacts 36, 38 and terminate operation of the conditioning equipment.

To calibrate the device, the screw 58 is merely rotated with respect to its mounting flange 60. This causes

a slight rotation of the lever 24 about shaft 20 thereby moving contact 36 relative to contact 38. It is apparent that by adjustment of screw 58 the contacts 36, 38 can be closed at any desired position of the cover member 66.

A positive "Off" means is provided to insure disengagement of the contacts 36, 38 when the cover 66 is rotated to its extreme counterclockwise position. More particularly, an arm 79 projects from lever 24 and is adapted to engage the U-shaped armature 40 to restrain the contact 36 from engagement with contact 38 when the cover is rotated to this position.

The device thus far described is adapted to control the ambient temperature about a setting of pointer 78. Means is also provided to indicate the ambient temperature completely independent of the temperature control means. To this end, a bimetal coil 84 is attached to a reduced portion 86 of shaft 20 and is provided with an indicator 88 attached to an end thereof. The indicator 88 is adapted to be moved by the bimetal coil 84 relative to the scale 76 in response to the ambient temperature to indicate the same. A decorative cover 90 is connected to shaft 20 by fastening means 92. A transparent plastic crystal 94 is positioned in the cup portion of cover 66 to shield the parts therefrom while permitting external viewing of the dial face 74. A series of ports 96 are provided in the cup portion of cover 66 to permit the free flow of air to the bimetal coil 84. These ports are shielded by the peripheral flange 72 on cover 66.

In operation, current is supplied from an external source (not shown) and passes through a conductor 98 to a terminal 100 which is mounted on the base 12. A lead 102 connects the terminal 100 to the lever 24. Current then flows from lever 24 through bimetal 32 to contact 36. When contact 36 is in engagement with contact 38, current will flow from contact 38 through support member 48 and a bus bar 104 which connects support member 48 with a terminal 106 mounted on base 12. Current then continues from terminal 106, out through conductor 108 to the conditioning equipment.

Assume an ambient temperature of 75° F. is desired. Cover 66 is merely rotated clockwise to set pointer 78 at 75° F. on scale 76. This rotation of cover 66 causes lever 54 to rotate counterclockwise, lever 24 to rotate clockwise, and movement of contact 36 into engagement with contact 38 to operate conditioning equipment in a manner hereinbefore described. When the ambient temperature reaches 75° F., the bimetal will be diametrically expanded with the inner high expanding surface tending to straighten the circular configuration. The contact 36 will then be moved upwardly and outwardly at approximately a 45° angle of contacts 38 to break the circuit and cease operation of the conditioning equipment.

Conversely, the contracting of the bimetal 32 due to cooling will close the contacts 36, 38. When the cover 66 is rotated to its extreme clockwise or "Off" position, the projection or arm 79 on lever 24 will engage the armature 40 to prevent contacts 36, 38 from closing.

In the event that service of the control device is required, the legs 22 of shaft 20 are merely extracted from the opening 18 in base 12 and the shaft 20 and the parts attached thereto are readily accessible to the serviceman.

While only a single embodiment of this invention has been shown and described herein, it is apparent that many changes may be made in the construction and operation without departing from the scope of this invention as defined in the appended claims.

We claim:

1. A thermostatic control device comprising a base member, first contact means carried by said base member, temperature setting means movably mounted on said base member and including a substantially circular cover member spaced from said base member for ambient air flow between said cover member and said base member, a bimetallic element secured to said temperature setting means and being disposed adjacent the space between said base member and said cover member, and second contact means carried by said bimetallic element and movable therewith relative to said first contact means in response to movement of said temperature setting means and in response to temperature variations of the air, said bimetallic element having a substantially circular configuration to provide a maximum area exposed to the air flowing between said base member and said cover member.

2. A thermostatic control device, the combination comprising a base member, first contact means carried by said base member, lever means rotatably mounted on said base member, a substantially circular cover member movably mounted on said base member and being spaced therefrom for ambient air flow between said cover member and said base member, said cover member engaging said lever means and being operable to cause rotational movement thereof, a temperature responsive element attached to said lever means and substantially encircling the same, said temperature responsive element being positioned adjacent the space between said cover member and said base member to provide maximum air exposure, and second contact means carried by said temperature responsive element and movable therewith relative to said first contact means in response to movement of said lever member and in response to variations in air temperature.

3. In a device for controlling operation of conditioning equipment, the combination comprising a base having a shaft extending outwardly therefrom, a substantially circular cover member rotatably mounted on said shaft and being spaced from said base for ambient air flow therebetween, cam means disposed in said cover member, a first lever pivotally mounted at its medial portion on said shaft between said base and said cover member, a second lever pivotally mounted on said base and operatively connected to said first lever and said cam means to cause movement of said first lever upon rotation of said cover member, a temperature sensitive bimetal having one end attached to an end of said first lever, said bimetal substantially encircling the first lever and being positioned adjacent the space between said base member and said cover member to provide a maximum area of air-exposed bimetal in a minimum space, and a pair of contacts one of which is secured to another end of said bimetal and the other being carried by said base, said one contact being positioned relative to said other contact by movement of said cover member whereby said one contact will engage said other contact to cause operation of the conditioning equipment at a predetermined air temperature.

4. The control device of claim 3 wherein the operative connection between said first and second levers comprises a screw threadedly mounted on said first lever, resilient means urging said screw into engagement with said second lever, said screw being adjustable to vary the position of said first lever relative to said second lever to calibrate the control device.
